(57) **CLAIM**

The ornamental design for a game piece, as shown and described.

DESCRIPTION

FIG. 1 is a top perspective view of the game piece, showing our new design;

FIG. 2 is a bottom perspective view of the game piece;

FIG. 3 is a front view of the game piece;

FIG. 4 is a left side view of the game piece;

FIG. 5 is a rear plan view of the game piece;

FIG. 6 is the right side view of the game piece;

FIG. 7 is the top view of the game piece; and,

FIG. 8 is the bottom view of the game piece.

The broken lines in the drawings illustrate portions of the game piece that form no part of the claimed design.
